UNITED STATES PATENT OFFICE.

FREDERICK SARGENT, OF EASTPORT, MAINE.

PARING KNIFE.

Application filed November 26, 1921. Serial No. 517,977.

To all whom it may concern:

Be it known that I, FREDERICK SARGENT, a citizen of the United States, and a resident of Eastport, in the county of Washington 5 and State of Maine, have invented a new and Improved Paring Knife, of which the following is a full, clear, and exact description.

This invention relates to improvements in paring knives, an object of the invention being to provide a device of this character which will facilitate the paring of fruit and vegetables in such a manner that there will be no waste in the parings, or in other words, a knife which is provided with improved 15 means for preventing the same from cutting too deeply into the article pared.

A further object is to provide a knife of this character which is particularly designed for paring vegetables or fruit having hollows therein, and a knife which will be exceedingly simple and practical in construction, durable and efficient in use, inexpensive to manufacture, and safe to use.

With these and other objects in view, the 25 invention consists in certain novel features of construction and combinations and arrangements of parts as will be more fully hereinafter described and pointed out in the claims.

30 In the accompanying drawings:

Figure 1 is a perspective view of my improved paring knife;

Figure 2 is a view in transverse section on the line 2—2 of Figure 1; the dotted lines 35 indicating an article in the process of being pared; and

Figure 3 is a view in section on the line 3—3 of Figure 1.

Referring in detail to the drawings, my 40 improved knife is equipped with a handle 1, of any approved material and shape. The invention resides in the particular shape of the knife itself and in the novel construction of guard which is utilized for regulating the 45 depth of cut of the knife. It will be seen that this guard includes a length of wire secured in one end of the handle member in any approved manner. This wire extends for a short distance at an angle to the longitudinal plane of the handle member, as 50 seen at 2, and then includes a relatively long straight portion 3 parallel to the longitudinal plane of the handle and offset therefrom. At the free end of the wire the same is bent 55 or curved gradually back toward the central longitudinal axis of the handle, as seen at

4, and the extremity of the guard is located over the outer end of the straight portion 3.

The knife designated by the reference numeral 5 is integral at each end with the 60 wire guard, one end of the knife merging into the guard adjacent its point of connection with the handle member, as indicated at 6. The knife preferably is constructed from the same piece of wire which 65 forms the guard and adjacent its point of junction with the guard is substantially circular in cross section. The main cutting portion of the knife, however, is of triangular cross section, as seen most clearly in 70 Figure 2, and includes a relatively sharp cutting edge 7 presented toward and offset from the straight portion 3 of the guard. The knife is parallel to the straight portion 75 of the guard and offset therefrom so that the guard may regulate its depth of cutting. At its outer end, the knife is curved in conformity with the shape of the free end of the guard, as seen at 8 in Figure 1 and merges into the guard adjacent its extremity. The 80 curved portion 8 of the knife is also offset from the curved portion 4 of the guard.

The ordinary manner of use of the knife will be apparent from the foregoing description. The curved portion of the knife is 85 particularly useful in scooping eyes from potatoes, or in paring fruit or vegetables having hollows therein since this curved end of the knife will readily fit into a hollow 90 and pare the skin cleanly from the same.

It might also be noted that the positioning of the cutting edge of the blade of the knife practically eliminates the danger of the user cutting himself accidentally. The hooked extremity 4 of the guard not only serves the 95 usual purpose when scooping eyes from potatoes or paring hollows in vegetables, but may also be conveniently used as a grip by the forefinger of an operator for more firmly gripping the knife.

Although I have illustrated one of the preferred embodiments of my invention, it will be evident that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended 105 claims.

I claim:

1. As a new article of manufacture, a paring knife including a handle and an integral blade and guard member carried thereby
5 constructed from a single length of wire bent upon itself to dispose the leads thereof in parallel relation, one of said leads cut away and beveled to provide a cutting blade having its cutting edge presented toward and
10 spaced from the guard member.
2. A paring knife constructed from a single length of wire bent upon itself to provide an integral blade and guard member constituting the parallel arranged leads
15 on said wire, one of which is cut away and beveled to provide a cutting blade having its cutting edge presented toward and spaced from the opposite lead which consti-

tutes the guard member, said leads being offset at one extremity, and a handle attached to said offset extremity. 20

3. A paring knife constructed from a single length of wire bent upon itself to provide an integral blade and guard member constituting the parallel arranged leads on 25 said wire, one of which is cut away and beveled to provide a cutting blade having its cutting edge presented toward and spaced from the opposite lead which constitutes the guard member, said leads being offset at 30 one extremity, and a handle attached to said offset extremity, the opposite ends of said leads having complementary parallel curved portions terminating in the bight of the wire to afford a finger rest for the user.

FREDERICK SARGENT.
